UNITED STATES PATENT OFFICE.

OTTO JAEGER, OF OGONTZ, PENNSYLVANIA.

MERCHANDISE-EXHIBITOR.

No. 826,251.

Specification of Letters Patent.

Patented July 17, 1906.

Application filed May 10, 1905. Serial No. 259,685.

To all whom it may concern:

Be it known that I, OTTO JAEGER, a citizen of the United States, residing at Ogontz, county of Montgomery, and State of Pennsylvania, have invented a certain new and useful Improvement in Merchandise-Exhibitors, of which the following is a specification.

My invention relates to a new and useful improvement in merchandise-exhibitor, and is intended as an improvement over a patent application filed by me February 18, 1905, Serial No. 246,243, for a revolving show-case; and the object of this invention is to provide an elastic means for securing the articles of merchandise against the curved surface of the exhibitor.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a horizontal section through my improved merchandise-exhibitor; Fig. 2, a side elevation of the same, the lower portion being broken away and shown in section.

A represents the exhibitor, which is preferably semicircular in form, and against the outside curved surface of the same the articles of merchandise B are to be held and exhibited. This exhibitor may either revolve within a case, as in my former application, or made with or without a case and stationary. At the lower end of the exhibitor is a projecting annular flange A', upon which the articles of merchandise are adapted to rest. If there are to be several tiers of these articles, one above the other, supplementary annular flanges A² may be secured to the outside surface of the exhibitor, upon which the successive tiers rest.

In Fig. 2 I have shown an exhibitor in which two tiers of articles are shown.

Extending across the open part of the exhibitor, at the rear thereof, are the tubes C, which tubes are secured at each side to the exhibitor, and thus serve to strengthen the same. D represents springs arranged within the tube, each spring being secured at the center of the tube, as shown at D'. The other end of each spring is secured to one end of a flexible cord, chain, tape, or the like, as represented at E, which extends out of each end of the tube and around the outside of the articles of merchandise, as shown in Fig. 1, and the tension of the springs pulling upon each end of the flexible connection serves to hold this flexible connection tightly against the articles of merchandise, and thus bind the articles against the curved surface of the exhibitor; but whenever the article is desired to be removed from the exhibitor the flexible connection E will give as the article is pulled out, as shown in Fig. 2, and any article can thus be removed, and the springs will at once take up the slack after the article is removed and hold the balance of the articles in their respective positions, where, if the holder was non-elastic, if a number of the articles were removed the other articles would be likely to topple over and fall out of the exhibitor.

Having thus fully described my invention, what I claim as new and useful is—

A merchandise-exhibitor approximately semicircular in form, supporting means carried by the exhibitor, tubes connecting the free ends of the exhibitor and acting as braces therefor, a spring means arranged within each tube, and a flexible member having each end extending within a tube, and secured to a spring means, said flexible member extending around the exterior surface of the exhibitor.

In testimony whereof I have hereunto affixed my signature in the presence of two subscribing witnesses.

OTTO JAEGER.
